SUPPORTING SPRING CUSHION STRUCTURE
FOR A SEATClair S. Reed, Wayne, Mich., assignor to Van Dresser
Specialty Corporation, Warren, Mich., a corporation
of MichiganFiled Nov. 27, 1962, Ser. No. 240,274
7 Claims. (Cl. 267—103)

This invention relates generally to spring cushions, and refers more particularly to an improved supporting spring cushion structure for a seat.

One of the essential objects of the invention is to provide an improved supporting spring cushion structure of the type mentioned wherein a single composite layer, embodying reinforcing load supporting heavy gauge spring wires, serves as the sole supporting spring structure for the seat and provides the desired cushioning effect.

Another object is to provide a supporting spring cushion structure wherein the single composite layer is provided throughout its length with a preformed transversely curved upwardly arched concavo-convex load carrying upper portion, and is provided throughout the length of opposite longitudinal side edges of said concavo-convex portion with opposed preformed downwardly and inwardly extending portions for supporting the concavo-convex upper portion.

Another object is to provide a supporting spring cushion structure wherein the downwardly and inwardly extending portions are attachable to a seat pan by means of suitable tongues or clips struck out from said seat pan.

Another object is to provide a supporting spring cushion structure that is simple in construction, economical to manufacture, and durable and efficient in use.

Other objects, advantages and novel details of construction of this invention will be made more apparent as this description proceeds, especially when considered in connection with the accompanying drawings wherein:

FIGURE 1 is a fragmentary top plan view of a supporting spring cushion structure for a seat, and showing portions of the single composite layer and anchoring wires broken away.

FIGURE 2 is a transverse sectional view taken substantially on the line 2—2 of FIGURE 1.

FIGURE 3 is a fragmentary transverse sectional view through the pan and showing one of the anchoring tongues or clips struck out from the pan to receive an anchoring wire for the single composite layer.

FIGURE 4 is a view similar to FIGURE 3 but showing the tongue or clip bent over and embracing an anchoring wire for the single composite layer.

FIGURE 5 is a top plan view of the structure illustrated in FIGURE 4.

FIGURE 6 is a fragmentary top plan view of a slightly modified supporting spring cushion structure for a seat, and showing portions of the single composite layer, anchoring wires, and border wire broken away.

FIGURE 7 is a transverse sectional view taken substantially on the line 7—7 of FIGURE 6.

Referring now to the drawings, A is an elongated substantially rectangular seat pan formed from sheet metal, and B is a strip formed from sheet metal, having portions 10 and 11 extending longitudinally of the seat pan adjacent the longitudinal edges thereof, having portions 12 and 13 extending transversely of the seat pan adjacent the transverse edges thereof, and having curved portions 14, 15, 16 and 17 respectively adjacent the corners of the seat pan and extending endwise from the longitudinally and transversely extending portions 10, 11, 12 and 13. Preferably the strip B is provided throughout its length with an upright web 18 and is provided at the lower and upper edges of said web with oppositely extending lat-

2

eral flanges 19 and 20. The lower lateral flange 19 is welded to the seat pan A while the upper lateral flange 20 cooperates with the seat pan to provide an outwardly opening channel 21. Located within this channel 21 is a suitable fiber tacking strip 22 that is secured to the web 18 by any suitable means (not shown). The exterior trim material (not shown) for the seat is secured to this tacking strip 22. If desired, the seat pan A may be provided with transversely spaced longitudinally extending depressed portions (not shown) for strengthening purposes.

A supporting spring cushion C, substantially rectangular shape in top plan, is located upon the seat pan A within the area enclosed by the strip B. Preferably this spring cushion C comprises a single composite layer 24 that serves as the sole supporting spring structure for the seat and that provides the desired cushioning effect.

As shown, the single composite layer 24 of this spring cushion is provided throughout its length with a preformed transversely curved upwardly arched concavo-convex load carrying upper portion 25, and is provided throughout the length of opposite longitudinal side edges of said concavo-convex portion 25 with opposed preformed downwardly and inwardly extending open return bent portions 26 and 27 for supporting the concavo-convex upper portion 25.

Such downwardly and inwardly extending open return bent portions 26 and 27 are provided throughout their lower longitudinally extending edges with heavy gauge anchoring wires 28 and 29 that are secured to the seat pan A by means of longitudinally spaced inverted substantially C-shaped tongues or clips 30 that are struck out from the seat pan A and that are bent over the anchoring wires 28 and 29 to embrace the same.

In addition to the anchoring wires 28 and 29, the single composite layer 24 of the spring cushion preferably comprises a longitudinally extending sheet 31 of fabric, and longitudinally spaced load carrying reinforcing heavy gauge spring wires 32 threaded transversely through the sheet 31 throughout its length and terminally connected to the anchoring wires 28 and 29.

The sheet 31 of fabric may be burlap or any other suitable material. The reinforcing wires 32 may be helical, spiral, sinuous, undulated or straight, as desired, and may be formed from any heavy gauge spring metal or other suitable material consistent with resiliency and the strength required to serve as spring supports. Preferably, the reinforcing wires 32 may be eight, nine or ten gauge spring steel, and may be approximately $\frac{1}{8}$ " in diameter.

The anchoring wires 28 and 29 are preferably covered or wrapped with paper 33 and may be any desired shape in cross section and of any heavy gauge steel to provide the proper strength. Preferably, the anchoring wires 28 and 29 may be eight, nine or ten gauge spring steel, and may be approximately $\frac{1}{8}$ " in diameter.

In use, the single composite layer 24 serves as a supporting cushion for the seat upholstery (not shown) such as the usual cotton layer, sponge rubber layer, and exterior trim of a seat, and such exterior trim may be secured by any suitable means (not shown) to the fiber tacking strip 22 in the outwardly opening channel 21.

In FIGURES 6 and 7, I have shown a slight modification wherein a supporting spring cushion D substantially rectangular shape in top plan, is placed upon a seat pan E corresponding in construction to the seat pan A, and is located within the area enclosed by a strip F corresponding in construction to the strip B. Preferably this spring cushion D comprises a single composite layer 41 that serves as the sole supporting spring structure for the seat and that provides the desired cushioning effect.

As shown, the single composite layer 41 of this spring cushion is provided throughout its length with a preformed transversely curved upwardly arched concavo-convex load carrying upper portion 42, and is provided throughout the

length of opposite longitudinal side edges of said concavo-convex portion 42 with opposed preformed downwardly and inwardly extending outwardly opening substantially V-shaped portions 43 and 44 for supporting the concavo-convex upper portion 42.

The lower sections 45 and 46 of the outwardly opening substantially V-shaped portions 43 and 44 are horizontal and are provided throughout their outer longitudinally extending edges with heavy gauge anchoring wires 47 and 48 that are secured to the seat pan E by means of longitudinally spaced inverted substantially C-shaped tongues or clips 49 that are struck out from the seat pan E and that are bent over the anchoring wires 47 and 48 to embrace the same.

In addition to the anchoring wires 47 and 48, the single composite layer 41 of the spring cushion preferably comprises a longitudinally extending sheet 50 of fabric, longitudinally spaced load carrying heavy gauge sinuous reinforcing spring wires 51 threaded transversely through the sheet 50 throughout its length and terminally connected to the anchoring wires 47 and 48, and a horizontally extending border wire 52 at the outer side edges of the concavo-convex portion 42 and secured by hog rings 53 to the transversely extending sinuous reinforcing wires 51.

The sheet 50 of fabric may be burlap or any other suitable material. The sinuous reinforcing wires 51 may be formed from any heavy gauge spring metal or other suitable material consistent with resiliency and the strength required to serve as spring supports. The anchoring wires 47 and 48 are preferably covered or wrapped with paper 55 and may be any desired shape in cross section and of any heavy gauge steel to provide the proper strength. The border wire 52 may be any suitable gauge spring steel and any desired shape in cross section, and is preferably covered or wrapped with paper 56. Preferably, the anchoring wires 47 and 48 and the reinforcing wires 51 may be eight, nine or ten gauge spring steel, and may be approximately $1/8$ " in diameter.

In use, the single composite layer 41 serves as a supporting cushion for the seat upholstery (not shown) such as the usual cotton layer, sponge rubber layer, and exterior trim material for the seat, and such exterior trim material may extend over the border wire 52 and may be secured by any suitable means (not shown) to the fiber tacking strip 57 in the outwardly opening channel 58 formed by the strip F and the seat pan E.

What I claim as my invention is:

1. In combination, an elongated seat pan, a single elongated composite layer embodying reinforcing load supporting heavy gauge spring wires and extending lengthwise of said seat pan, said composite layer being provided throughout its length with a preformed transversely curved upwardly arched concavo-convex load carrying upper portion and provided throughout the length of opposite longitudinal side edges of said concavo-convex portion with opposed preformed downwardly and inwardly extending open return bent portions for supporting the concavo-convex upper portion, said downwardly and inwardly extending open return bent portions being provided throughout their lower longitudinally extending edges with heavy gauge anchoring wires, and means securing said anchoring wires to said seat pan including longitudinally spaced substantially C-shaped tongues struck out from the seat pan and bent over said anchoring wires to embrace the same.

2. In combination, an elongated seat pan, a single elongated composite layer embodying reinforcing load supporting heavy gauge spring wires and extending lengthwise of said seat pan, said composite layer being provided throughout its length with a preformed transversely curved upwardly arched concavo-convex load carrying upper portion and provided throughout the length of opposite longitudinal side edges of said concavo-convex portion with opposed preformed downwardly and inwardly extending outwardly opening substantially V-

shaped portions for supporting the concavo-convex upper portion, the lower sections of said outwardly opening substantially V-shaped portions being horizontal and being provided throughout their outer longitudinally extending edges with heavy gauge anchoring wires, and means securing said anchoring wires to said seat pan including longitudinally spaced substantially C-shaped tongues struck out from the seat pan and bent over said anchoring wires to embrace the same.

3. In combination, an elongated seat pan, a single elongated composite layer extending lengthwise of said seat pan, said composite layer being provided throughout its length with a preformed transversely curved upwardly arched concavo-convex load carrying upper portion and provided throughout the length of opposite longitudinal side edges of said concavo-convex portion with opposed preformed downwardly and inwardly extending open return bent portions for supporting the concavo-convex upper portion, said downwardly and inwardly extending open return bent portions being provided throughout their lower longitudinally extending edges with heavy gauge anchoring wires, said single composite layer comprising a longitudinally extending sheet of fabric and longitudinally spaced load carrying reinforcing heavy gauge spring wires threaded transversely through said sheet throughout its length and terminally connected to said heavy gauge anchoring wires, and means securing said anchoring wires to said seat pan including longitudinally spaced substantially C-shaped tongues struck out from the seat pan and bent over said anchoring wires to embrace the same.

4. In combination, an elongated seat pan, a single elongated composite layer extending lengthwise of said seat pan, said composite layer being provided throughout its length with a preformed transversely curved upwardly arched concavo-convex load carrying upper portion and provided throughout the length of opposite longitudinal side edges of said concavo-convex portion with opposed preformed downwardly and inwardly extending outwardly opening substantially V-shaped portions for supporting the concavo-convex upper portion, the lower sections of said outwardly opening substantially V-shaped portions being horizontal and being provided throughout their outer longitudinally extending edges with heavy gauge anchoring wires, said single composite layer comprising a longitudinally extending sheet of fabric, longitudinally spaced load carrying sinuous reinforcing heavy gauge spring wires threaded transversely through said sheet throughout its length and terminally connected to said heavy gauge anchoring wires, and a horizontally extending border wire at the outer side edges of the concavo-convex portion and secured to the transversely extending sinuous heavy gauge reinforcing wires, and means securing said anchoring wires to said seat pan including longitudinally spaced substantially C-shaped tongues struck out from the seat pan and bent over said anchoring wires to embrace the same.

5. In combination, an elongated substantially rectangular seat pan, a sheet metal strip having portions secured to and extending longitudinally of the seat pan adjacent the longitudinal edges thereof, having portions secured to and extending transversely of the seat pan adjacent the transverse edges thereof, and having curved portions secured to said seat pan adjacent the corners thereof and extending endwise from the longitudinally and transversely extending portions aforesaid, an elongated spring cushion located upon the seat pan within the area enclosed by said strip, said spring cushion comprising a single elongated composite layer embodying reinforcing load supporting heavy gauge spring wires, said composite layer being provided throughout its length with a preformed transversely curved upwardly arched concavo-convex load carrying upper portion and being provided throughout the length of opposite longitudinal side edges of said concavo-convex portion with opposed preformed

downwardly and inwardly extending open return bent portions for supporting the concavo-convex upper portion, said downwardly and inwardly extending open return bent portions being provided throughout their lower longitudinally extending edges with heavy gauge anchoring wires, and means securing said anchoring wires to said seat pan including longitudinally spaced substantially C-shaped tongues struck out from the seat pan and bent over said anchoring wires to embrace the same.

6. In combination, an elongated substantially rectangular seat pan, a sheet metal strip having portions secured to and extending longitudinally of the seat pan adjacent the longitudinal edges thereof, having portions secured to and extending transversely of the seat pan adjacent the transverse edges thereof, and having curved portions secured to said seat pan adjacent the corners thereof and extending endwise from the longitudinally and transversely extending portions aforesaid, an elongated spring cushion located upon the seat pan within the area enclosed by said strip, said spring cushion comprising a single elongated composite layer embodying reinforcing load supporting heavy gauge spring wires, said composite layer being provided throughout its length with a preformed transversely curved upwardly arched concavo-convex load carrying upper portion and being provided throughout the length of opposite longitudinal side edges of said concavo-convex portion with opposed preformed downwardly and inwardly extending outwardly opening substantially V-shaped portions for supporting the concavo-convex upper portion, the lower sections of said outwardly opening substantially V-shaped portions being horizontal and being provided throughout their outer longitudinally extending edges with heavy gauge anchoring wires, and means securing said anchoring wires to said wires, and means securing said anchoring wires to said seat pan including longitudinally spaced substantially C-shaped tongues struck out from the seat pan and bent over said anchoring wires to embrace the same.

7. In combination, an elongated substantially rectangular seat pan, an elongated sheet metal strip having portions extending longitudinally of the seat pan adjacent the

longitudinal edges thereof, having portions extending transversely of the seat pan adjacent the transverse edges thereof, and having curved portions adjacent the corners of said seat pan and extending endwise from the longitudinally and transversely extending portions aforesaid, said elongated strip being provided throughout its length with an upright web and provided at the lower and upper edges of said web with oppositely extending lateral flanges, the lower lateral flanges being welded to said seat pan, the upper lateral flanges cooperating with said seat pan to provide an outwardly opening channel, an elongated spring cushion located upon the seat pan within the area enclosed by said elongated strip, said spring cushion comprising a single elongated composite layer embodying reinforcing load supporting heavy gauge spring wires, said composite layer being provided throughout its length with a preformed transversely curved upwardly arched concavo-convex load carrying upper portion and being provided throughout the length of opposite longitudinal side edges of said concavo-convex portion with opposed preformed downwardly and inwardly extending portions for supporting the concavo-convex upper portion, said downwardly and inwardly extending portions being provided throughout their length with heavy gauge anchoring wires, a tacking strip for trim material for the spring cushion located within said outwardly opening channel and secured to said upright web, and means securing said anchoring wires to said seat pan including longitudinally spaced substantially C-shaped tongues struck out from the seat pan and bent over said anchoring wires to embrace the same.
